COMBINED AEROSOL ACTUATOR AND DISPENSER FOR MEDICAMENTS

Kenneth J. Gurian, Encino, and Robert W. Service, Burbank, Calif., assignors to Riker Laboratories, Inc., Northridge, Calif., a corporation of Delaware

Filed June 8, 1962, Ser. No. 70,483

Term of patent 14 years

(Cl. D83—1)

FIG. 1

FIG. 2

FIG. 3

FIG. 4

FIG. 1 is a front perspective view of a combined aerosol actuator and dispenser for medicaments embodying our new design;

FIG. 2 is a front elevational view;

FIG. 3 is a side elevational view; and

FIG. 4 is a top plan view thereof.

The undisclosed bottom portion of the medicament chamber is substantially flat and unornamented.

We claim:

The ornamental design for a combined aerosol actuator and dispenser for medicaments, substantially as shown and described.
